UNITED STATES PATENT OFFICE.

NELSON B. HENRY, OF DALLAS, TEXAS, ASSIGNOR TO MURRAY COMPANY, OF DALLAS, TEXAS, A CORPORATION OF TEXAS.

STEAM-CUSHION VALVE.

1,132,718.

Specification of Letters Patent. Patented Mar. 23, 1915.

Application filed July 24, 1914. Serial No. 852,903.

To all whom it may concern:

Be it known that I, NELSON B. HENRY, a citizen of the United States, residing at Dallas, in the county of Dallas and State of Texas, have invented certain new and useful Improvements in Steam-Cushion Valves, of which the following is a specification.

My invention relates to a new and useful steam cushion valve, and its object is to provide a steam cushion valve that will serve to automatically retard the exhaust from a cylinder as the piston approaches one of the cylinder heads, thereby opposing a steam cushion to the upward movement of the piston, and preventing such impact of the piston with the cylinder head as might loosen or detach the head.

A further object of the invention is to provide a device of the character described that will be particularly adapted for use in conjunction with the cylinder of a steam actuated cotton press tamper.

It is finally the object of my invention to provide a device of the character described, that will be strong, durable, simple and efficient and comparatively easy to construct, and also one that will not be likely to get out of working order.

With these and various other objects in view, my invention has relation to certain novel features of construction and use, an example of which is described in the following specification, and is illustrated in the accompanying drawing, wherein:

Figure 1 is a top view of a vertical steam cylinder such as commonly used in conjunction with a cotton press. Fig. 2 is a view of the same in side elevation. Fig. 3 is an ax- ial vertical sectional view of my improved steam cushion valve showing a portion of the cylinder carrying said valve and a portion of the reciprocating members within said cylinder.

Referring now more particularly to the drawing, wherein like reference characters designate similar parts in all the figures, the numeral 1 denotes an elongated vertical steam cylinder, the heads of which are indicated at 1^a. Within said cylinder is mounted a reciprocating piston 2 fast upon the upper end of an elongated piston rod 3 passing slidably through the lower cylinder head. The upper head of the cylinder is

formed with a central aperture threaded to receive the lower portion of a nipple 4. The upper portion of the nipple 4 is threaded into the lower end of a valve casing 5 having a vertical bore 6 the axis of which is coincident with that of the cylinder, the diameter of said bore being somewhat greater than the interior diameter of the nipple 4. The bore 6 extends to the top of the casing 5 and is threaded at its upper end to receive a plug 7.

Through the passage established by the nipple 4, there is passed a tubular plunger 8, the exterior diameter of the plunger being slightly less than the interior diameter of the nipple. This plunger is shown in Fig. 70 3 as occupying the uppermost limiting position of a certain vertical displacement to which the plunger is periodically subjected in the use of my device. In the same figure there is also indicated in dash lines the 75 lowermost limiting position which the plunger is adapted to assume. Adjacent to each of its extremities, (both of which are open) the plunger rod 8 is formed with several steam ports 9. The upper extremity 80 of the plunger rod is exteriorly threaded to receive a plunger head 10, which is adjusted upon said rod to a position just below the ports 9, as is clearly shown in Fig. 3, the diameter of the plunger head 10 being slightly 85 less than that of the bore 6. When the parts 8 and 10 are in their lowermost positions, the plunger head is seated upon the shoulder formed by the juncture of the bore 6 with the passage of the nipple 4, and the 90 plunger rod extends for some distance into the cylinder 1 as indicated in dash lines in Fig. 3. The movement of the members 8 and 10 from their lowermost to their uppermost positions is actuated by the piston 95 2 as it approaches the upper head 1^a, and the return motion of the parts 8 and 10 to their lowermost position is actuated both by the weight of said parts and by a preponderance of steam pressure above the collar produced in a manner hereinafter made clear, said return motion taking place during the initial portion of the downward stroke of the piston 2. Adjacent to the lower extremity of the bore 6, it has communication with a horizontally extending orifice 11, which orifice communicates with a pipe 12, through which steam may pass

to or from my valve. The orifice 11 has communication with the lower end of a vertical tubular steam passage 13, having its upper portion somewhat larger in diameter than the lower portion, thereby producing an annular shoulder 14 forming a seat for a valve ball 15. The passage 13 is extended to the top of the body 5 and is threaded at its upper end to receive a plug 17. The upper portion of the passage 13 has communication through an upwardly inclined tubular orifice 16 with the upper end of the bore 6 (see Fig. 3).

The structural features of my invention having been above fully described, an explanation will now be given as to the operation of the device. When the parts 2, 3, 8 and 10 are in their uppermost positions as illustrated in the drawings, steam is conducted to my valve through the pipe 12. Since only a small portion of the steam may flow into the cylinder 1 through the space intervening between the plunger rod 8 and the nipple 4, the pressure of steam will raise the ball 15 and the steam will find a passage into the upper portion of the bore 6 through the openings 13 and 16. It will then enter the interior passage of the tubular rod 8 through the upper ports 9 and will escape into the upper portion of the cylinder 1 through the lower ports 9. The piston 2 will now begin its downward stroke, the members 8 and 10 riding down upon it until the member 10 seats itself in the lower end of the bore 6. When the parts 8 and 10 reach this position, the steam will enter the cylinder 1 with increased volume since it may flow through the orifice 11 downwardly into the top of the member 8. When the piston 2 is making its upward stroke (produced by admission of steam to the lower end of the cylinder 1 through the pipe 18), the pipe 12 serves to conduct away the exhaust steam, and until the piston has almost completed its upward stroke, the steam will exhaust freely through the tubular plunger rod 8 and through the orifice 11 into the pipe 12. During the final portion of the upward stroke of the piston 2, the members 8 and 9 will ride up upon the piston, and when the plunger head 10 in its upward movement has crossed the orifice 11 the steam must exhaust upwardly through the slight space intervening between the piston head 10 and the wall of the bore 6. The exhaust of steam during the final portion of the upward stroke of the piston 2 will thus be sufficiently retarded to cushion the force acting upwardly upon the piston so that its upward stroke may terminate without forcible impact of the piston against the upper cylinder head.

The invention is presented as including all such modifications and changes as properly come within the scope of the following claims.

What I claim is:

1. In a device of the character described, the combination with a vertical steam cylinder, and a piston reciprocatory within the same, of a valve casing surmounting the cylinder formed with a vertical bore and having a discharge orifice in communication with the bore, a tubular steam conducting plunger rod passing vertically through a passage establishing communication between the cylinder and bore and having an exterior diameter slightly less than the diameter of the passage, a steam port being formed in said plunger at each end thereof, and a plunger head rigidly carried by the upper end of the plunger rod beneath the upper port, the plunger rod being proportioned to project into the cylinder in its lowest position, in which position the plunger head occupies a position below the discharge orifice, the plunger rod and plunger being displaced upwardly by the piston in the final portion of its upward stroke, shifting the plunger head to a point above the discharge orifice. 90

2. In a device of the character described, the combination with a vertical steam cylinder, and a piston reciprocatory within the same, of a valve casing surmounting the casing formed with a vertical bore and having a discharge orifice in communication with the bore, and further formed with a steam passage connecting the upper end of the bore with the discharge orifice, a valve interposed in said steam passage allowing a flow of steam to the bore but preventing a flow in the other direction, means for conducting steam to or from the discharge orifice, a tubular steam conducting plunger rod passing vertically through a passage establishing communication between the cylinder and bore, and having an exterior diameter slightly less than the diameter of said passage, a steam port being formed in said rod at each extremity, and a plunger head rigidly carried by the upper end of the plunger rod beneath the upper port, the plunger rod being proportioned to project into the cylinder in its lowest position, in which position, the plunger head occupies a position below the discharge orifice, said rod and plunger being displaced by the piston in the final portion of its upward stroke shifting the piston to a point above the discharge orifice. 100

3. In a device of the character described, the combination with a vertical steam cylinder and a piston reciprocatory within the same, of a valve casing surmounting the cylinder formed with a vertical bore and having a discharge orifice in communication with the bore, a tubular steam conducting rod passing vertically through a passage establishing communication between the cylinder and bore, and having an exterior di- 125

ameter slightly less than the diameter of the passage, a steam port being formed in said plunger at each end, a plunger head rigidly carried by the upper end of the plunger rod 5 beneath the upper port, the plunger rod being proportioned to project into the cylinder in its lowest position in which position the plunger rod occupies a position below the discharge orifice, said rod and the plunger head being displaced upwardly by the piston in the final portion of its upward stroke, shifting the plunger head to a point above the discharge orifice, the valve body being formed with a passage communicating 10 with the upper portion of the bore, through which steam may be admitted thereto.

4. In a device of the character described, the combination with a vertical steam cylinder and a piston reciprocatory within the 20 same, of a valve casing surmounting the cylinder formed with a vertical bore and having a discharge orifice in communication with the bore, a tubular steam conducting

plunger rod passing vertically through a passage establishing communication between 25 the cylinder and bore, a small flow of steam being possible between said rod and the wall of said passage, a steam port being formed in said rod at each end thereof, and a plunger head rigidly carried by the upper end of 30 the rod beneath the upper port, said rod being proportioned to project into the cylinder in its lowest position, in which position the plunger head occupies a position below the discharge orifice, the plunger rod and plunger being displaced upwardly by the piston during the final portion of its upward stroke, shifting the plunger head to a point above the discharge orifice.

In testimony whereof I have signed my 40 name to this specification in the presence of two subscribing witnesses.

NELSON B. HENRY.
